UNITED STATES PATENT OFFICE.

ELLIS D. ALLENSTWORTH, OF WAUKEGAN, ILLINOIS.

IGNITING AND SPARK-DISTRIBUTING DEVICE.

1,213,790.

Specification of Letters Patent.

Patented Jan. 23, 1917.

Application filed January 3, 1916. Serial No. 69,785.

To all whom it may concern:

Be it known that I, ELLIS D. ALLENSTWORTH, a citizen of the United States, residing at Waukegan, in the county of Lake and State of Illinois, have invented certain new and useful Improvements in Igniting and Spark-Distributing Devices, of which the following is a specification.

My invention relates to engine igniting and spark distributing devices for plural cylinder internal combustion engines, wherein ignition is effected in sequential order in the various cylinders of said engine by sparks produced in an electric circuit periodically interrupted by a mechanical circuit breaker positively initiated by the engine at definite periods of time and automatically continued by the effect of the electric current.

20 One of the general objects of my invention is to improve the construction and operation of devices of this character; to render the structure compact and the parts easy to assemble and readily accessible and to 25 cheapen the cost of production.

Another object and distinctive feature of my invention is to provide means whereby a spark is initiated by the engine and a plurality of sparks are automatically continued 30 thereafter to be made in each cylinder during the spark-time thereof, in each spark-time period in the cyclic operation of the distributor, thereby to produce better ignition by causing more rapid propagation of 35 the flame in the fired charge, and to increase the fuel efficiency.

Other and further objects of my invention will become readily apparent to persons skilled in the art from a consideration of the 40 following description when taken in conjunction with the drawings, wherein:

Figure 1 is a central vertical section taken on line 1—1 of Fig. 2. Fig. 2 is a transverse section taken on line 2—2 of Fig. 1. Fig. 45 3 is a transverse section taken on line 3—3 of Fig. 1. Fig. 4 is a transverse section taken on line 4—4 of Fig. 1. Fig. 5 is a detail of the primary circuit controlling engine-operated lever.

50 A collar 6 is secured to the engine driven shaft 7, by any suitable means, a screw 8 being shown for this purpose. The shaft 7 may be, for example, the valve operating shaft of an internal combustion engine, 55 which is rotated in proper time relation with the power shaft of the engine with

which the timer and distributor is to be associated.

The upper part 9 of the collar is reduced in diametric cross section to provide a shoulder 10. Upon the shoulder 10, and around the reduced portion 9 of the collar 6, is a ring 11, preferably of brass or Babbitt metal or similar material, which is loose upon the collar 9 and which is surrounded by hub 12 from the lower portion 13 of the casing 14, so that the casing 14 may be manually oscillated upon the collar 6 for the purpose of changing its rotative position with reference to the circuit breaking cam 15 to vary the spark lead.

60 A stud 16, which is concentric with the shaft 7, is provided on its lower end with an integral disk 18 whereby it is attached to the upper end 9 of the collar 6, as by 65 means of screws 19. The stud is threaded, as at 20, and carries a threaded circuit controlling cam 15 which is held in adjusted position by the check nut 21. The upper end 16' of the stud is reduced somewhat in 70 size and carries upon its upper end a commutating block of insulating material 22 which is secured in place on the stud, as by 75 means of a screw 23.

80 A removable part 13' of the casing consists of a disk 24 of insulating material and a surrounding metal cylinder 25. The cylinder 25 overlies a rim of the cylindrical portion 26 of the lower part 13 of the casing and is held in place thereon by means of the 85 studs 27—27 which pass through bayonet joint orifices provided in the cylinder 25, and when slightly rotated, is secured in place by means of the snap latch 28, which then passes over the end of the screw 29 that is 90 threaded into the cylindrical portion 26 of the lower portion 13 of the casing.

95 The distributor block 22, of insulating material, carries one terminal of the high potential circuit and is rotated directly by the 100 shaft 7. In the other end of the block is a spring pressed button 30 that fits loosely in a metallic, or other electrical conducting thimble 31, and is spring pressed by an underlying open helical spring 32. A plate 105 33 extends from the thimble 31 to the central portion of the block 22 under the block 38. A central terminal screw 35 is screw threaded on its outer end, its larger inner end 37 is hollow, as at 36, and contains an 110 open helical spring 37' which yieldingly presses the block 38, which may be of carbon

- or other suitable material, upon the upper surface of the plate 33 and thus completes the electric circuit between either of the terminals 40 through the button 30 to the central terminal 35. The terminal block 38 is in electrical connection with the terminal screw 35, to which a suitable electrical cable or wire (not shown) is to be connected. This cable leads to the source of the high potential circuit, as the return conductor for the other terminals 40 that are intended for connection with the spark plugs of the respective cylinders.
- Spaced around the insulating cover, or disk 24, at uniform distances apart, are a suitable number of terminal screws 40, the number depending upon the number of cylinders to be included in the engine with which the device is to be associated, the screw threaded portions of which screws are threaded into the disk 24 and bear heads 41 that are submerged in the insulating material of said disk, so that the outer surfaces of said heads are flush with the inner surface of said disk. In the rotation of the insulating block 22, by means of the shaft 7, and in cyclic unison with the reciprocation of the pistons of the engine, the spring pressed button 30 is brought in successive turns into contact with the heads 41 of the respective screws, in their regular sequential order, substantially as shown in Fig. 1, thereby completing the secondary electric circuit from the common return wire, which is to be connected to the screw 35 through the plate 33, the spring 32 and thimble 31 and the spring pressed button 30 to the respective spark plug terminal screws 40, in their sequential order.
- The primary circuit-breaking and controlling apparatus is located in the lower part 13 of the casing 14 and is initially operated by the engine driven cam 15. The cam 15 may be a substantially rectangular structure for a four cylinder engine, having rounded corners 42 and flat parallel opposite sides between the respective corners. An articulate, cam-operated lever 44 is pivoted to a stud 45, which stud is fixed in the lower part 50 of the casing 13, as at 46. The lever 44 consists of two plate-like members 47 and 48, held spaced apart by means of spacing sleeves 49 and rivets 50, between which members is placed a cam bearing-roller 51. The roller 51 is journaled upon the pin 52, that is fixed at its ends in the respective members 47 and 48. The free ends of the plates of the lever 44 are brought together, as at 53, and it is yieldingly held, at all times with the roller 51 bearing upon the cam 15, by means of a helical spring 54 which is secured to a pin 55 projecting from the casing member 13. The lever 44 is provided with a projecting end or nose 56 which normally bears upon the end of and restrains the vibrating

lever or armature 57. The lever or armature 57 consists of a strip of spring metal 58, such as steel, bronze or the like, secured to a projection from the frame 59, by means of the screw 60. It carries upon its outer end an iron, or soft steel armature 61 which overlies the poles 62-62 of an electro-magnet and which is responsive thereto. The electro-magnet, comprising poles 64 and 65, is composed of a series of magnetically permeable laminæ held together by rivets 67 and secured in the casing by screws 68. The magnet may be provided with a single electric coil 69, which is shown over the leg 65, or another coil may also be placed over the leg 64, if desired. One magnet coil, however, will be sufficient in some cases for the purpose desired. The armature 61 carries a contact point 70, which is movable with the armature and is adapted for electrical association with the relatively stationary contact point 71 secured on the end of the adjustable screw 72. The resilience of the spring plate 58 is sufficient to bring the contacts 70-71 together when the armature is released. The screw 72 is threaded in a metal thimble 73, which is secured in the removable insulating plate 74 of the casing. The screw 72 is adjustable and is held yieldingly in adjusted position by the open helical spring 75, which surrounds the shank of the screw and has bearing upon the thimble 73. The insulating plate 74 is easily removable, being secured to the casing by tongue and groove joint 76 and by the removable screw 78.

A top or cover plate 78' is pivoted to the casing, as at 79, and is adapted to be slid on the pivot thus afforded so as to expose the interior of the lower portion 13 of the casing, for inspection. The cover is held in closed position by a screw 80 that takes into the casing through a perforation provided in the cover.

Binding posts 81 and 82 are connected to the primary source of electric current and to a condenser 63, respectively, as shown, and are insulatedly secured to the lower portion 13 of the casing 14. A wire 83 connects binding post 81 with the coil 69, and wire 84 connects binding post 82 to the sleeve 73, and thereby to the contact point 71. Wire 85 connects wire 84 to the coil 69.

I have diagrammatically shown a schematic arrangement of circuits in which my distributor will produce desirable results, wherein post 81 is connected to battery B by wire *a*. The battery is connected to the primary coil P by wire *b*. Wire *c* connects the other terminal of coil P to one terminal of a condenser 63. The wire *c* is "grounded" between coil P and the condenser 63, as at G. The other terminal of the condenser is connected to post 82 by wire *d*. The terminals of the secondary coil S are to be connected 130

to the ground and to the terminal 35 of the distributor. The condenser bridges the contacts 70-71, prevents destructive sparking between the contacts 70-71 and enhances the current impulses in the primary circuit coil P when said contacts are opened and closed.

The operation of the device is as follows:—The primary circuit controlling cam 15 and the secondary cam, or block 22 are rotated together by means of a shaft 7. When the cam 15 is rotated so that the roller 51 rests upon one of the flat sides 43, the spring 54 will pull over the lever 44 and release the armature 61 so that the resilient effect of the spring 58 will produce electrical connection between the contacts 70 and 71 thereby closing the circuit through the electric coil 69. The magnet 64-65 will thereupon and immediately thereafter attract the armature 61 thus opening the circuit between the contact 70 and 71 and thereafter the spring and magnet will continue to operate the armature to produce rapid make-and-break of the circuit during the time that the flat portion 43 of the cam is traversing the roller 51, or while the lever 44 is retracted by the spring 54 from its contact with the armature when the armature is released, the circuit is very rapidly opened and closed, automatically thereby through the instrumentality of the electro-magnet, in the manner aforesaid, causing a corresponding number of impulses of current to flow in the primary circuit during the time of the circuit closing period, or during substantially the entire power stroke of the engine, thereby inducing a corresponding number of impulses of relatively high potential in the secondary circuit and a like number of sparks between the terminals of the respective spark plugs in the cylinders of the engine, during the respective spark-time cyclic periods. By this means a large number of sparks are produced in each cylinder at each time that a charge is to be ignited and persists until the effect of the charge is spent. A prolongation of the spark-time, by the number of intermittent impulses produced in the primary circuit automatically by the means heretofore described, operates to produce more certain and positive ignition of the charge, thereby accelerating the propagation of flame or hastening the time in which complete combustion will occur, thus causing a more rapid explosive expansion of the charge and hence increasing the efficiency of the fuel and of the engine. It is, of course, understood that the distributor 22 for the secondary circuit is operated in harmony with the primary circuit breaking device referred to, and that the said distributor directs the sparking effect consecutively into the respective cylinders, in the ordinary cyclic operation of such devices.

The high parts 42, of the cam 15, hold the primary circuit open, in the manner described, while the lower flat portions 43, of the cam permit the spring 54 to draw the end 56 of the lever 44 out of the path of the 79 armature 61 releasing the armature, permitting the spring blade 58 to close the electric circuit between the contacts 70 and 71, thereby completing the electric circuit. Thereafter the electromagnet 64-65 automatically 75 opens and closes the circuit rapidly a great number of times and continues to do so during the time that the projection 56, from the lever 44 is thus removed from the path of the armature 61.

The engine-driven cam 15 periodically releases the electro-magnetically responsive armature, which thereupon continues to be automatically vibrated by the electro-magnet until the armature is again restrained by 85 the cam lever 44. Each vibration of the armature produces a make and break in the primary circuit and a charge and discharge of the condenser with corresponding number of current impulses each of which results 90 in a spark in the secondary circuit at the respective spark plugs. Upon movement of the cam 15, by the engine, the armature is moved positively thereby and its vibration function stopped. Thus the engine causes 95 initiation of the automatically produced current impulses and after a desired interval of time, positively prevents their continuance.

While I have herein shown a single embodiment of my invention for the purpose 100 of clear disclosure, it is manifest that many changes may be made in the specific form and disposition of the parts within the scope of the appended claims.

Having described my invention, what I 105 claim is:—

1. An ignition timer and spark distributor comprising an electromagnet; a yielding armature adapted to normally close circuit through said electromagnet; means including a rotary cam to restrain the armature and hold it in open circuit position and a spring opposing said means for releasing said armature to permit the electromagnet to vibrate the armature.

2. An ignition timer and spark distributor comprising an electromagnet; a stationary contact; a yielding armature; a contact controlled by said armature normally connected to the stationary contact; means, including a rotary cam for disconnecting said contact and a spring opposing said means to separate it from said armature and permitting the electromagnet to vibrate the armature when the cam is moved.

3. An ignition timer and spark distributor comprising an electromagnet; a stationary contact; a yielding armature responsive to said magnet when unrestrained; a contact carried by the armature coöperating with 130

the stationary contact to close the circuit through said electromagnet; means, including a cam to restrain the armature and a spring opposing said means to release the armature and permit the electro-magnet to vibrate the armature when the cam is moved.

4. An ignition timer and spark distributor comprising an electromagnet; a stationary contact; a yielding armature responsive to 10 said magnet when unrestrained; a contact carried by the armature coöperating with the stationary contact to close the circuit through said electromagnet; a spring arranged to permit the armature to close said 15 contact and means including a rotary cam operable against the influence of said spring to restrain said armature and stop the electromagnet from vibrating the armature.

5. An ignition timer and spark distributor 20 comprising an electromagnet; an armature therefor adapted to normally close circuit through said electromagnet; means, including a rotary cam for positively holding the armature in open circuit position and a spring for releasing the armature when the cam is moved thereby permitting the electromagnet to vibrate the armature.

6. An ignition timer and spark distributor comprising an electromagnet; an armature

therefor adapted to normally close circuit 30 through said electromagnet; a lever adapted when moved by a cam to restrain the armature; a cam for moving said lever and a spring to move the lever to release the armature when the cam is moved.

35

7. In an ignition timer and spark distributor for an internal combustion engine, the combination of a circuit breaker comprising an armature to be automatically vibrated to make and break an electric circuit; an electromagnet in said circuit for producing the vibrations of said armature; a lever for restraining said armature, to hold said circuit open; a spring to move said lever to release the armature to permit it to 40 close and open said circuit when not opposed by said lever and a part operable by the engine to move said lever in an opposite direction against the efforts of said spring to permit said electromagnet to vibrate the 45 armature.

40

In testimony whereof I hereunto set my hand in the presence of two subscribing witnesses.
